US0D1077085S

(12) **United States Design Patent** (10) **Patent No.:** **US D1,077,085 S**
(45) **Date of Patent:** **** May 27, 2025**

(54) **TOY**

(71) Applicant: **Weixian Zhang**, Shantou (CN)

(72) Inventor: **Weixian Zhang**, Shantou (CN)

(**) Term: **15 Years**

(21) Appl. No.: **29/981,549**

(22) Filed: **Dec. 31, 2024**

(51) LOC (15) Cl. **21-01**

(52) U.S. Cl.

USPC **D21/615**

(58) **Field of Classification Search**

USPC D21/398, 576, 578, 584, 585, 615

CPC A63H 11/18; A63H 11/20; A63H 3/46;
